PUMPING MECHANISM

Ralph Horton, Groton, Conn., and Newton E. Spiess, Jr., Oakdale, and Kenneth R. Weaver, Bellport, N. Y., assignors to National Dairy Research Laboratories, Inc., Oakdale, N. Y., a corporation of Delaware

Application April 26, 1951, Serial No. 223,118

6 Claims. (Cl. 103—241)

1

The present invention relates to fluid pumping mechanisms and, more particularly, to mechanisms of such character wherein the pumping operation is effected by means of the application of fluid pressure to the fluid to be pumped. In certain operations, for example, in the dairy industry, it is desired to transport a fluid, such as cream, from one location to another. In this operation, the cream (or other fluid that is to be pumped) should be subjected to as little agitation as possible. For example, a satisfactory operating condition exists when the condition of the fluid and its agitation is no more than occasioned in flowing through a pipe line at normal velocities. It is also important to avoid the entrainment of air in the fluid and the rate of pumping should be capable of being controlled so that it will agree with the available volume of fluid that is supplied to the pump.

Accordingly, it is an object of the present invention to provide a pumping mechanism utilizing a fluid under pressure as the source of pumping energy and being of such character that the pumped fluid is maintained at desired optimum conditions throughout the pumping operation.

A further object of the invention is to provide a pumping mechanism of the above character wherein the entrainment of air in the fluid being pumped is avoided.

Yet another object of the invention is to provide a pumping mechanism of the above character by means of which the rate of pumping may be controlled effectively in accordance with the volume of fluid available to be pumped at any given time.

Another object of the invention is to provide a mechanism of the above character wherein agitation of the fluid being pumped is reduced to a minimum during the pumping operation.

Other and further objects of the invention will be apparent as it is described in greater detail in connection with the accompanying drawings, wherein

Figure 1 is a plan view of a pumping mechanism constructed in accordance with the present invention;

Figure 2 is a view in side elevation showing the pumping mechanism of Figure 1;

Figure 3 is a view in end elevation, partly broken away, to illustrate the interior of a portion of the pumping mechanism;

Figure 4 is a partial view in section, taken on the plane indicated by line 4—4 of Figure 1 and looking in the direction of the arrows;

Figure 5 is a partial view in section, taken on

the broken plane indicated by the line 5—5 of Figure 1, and looking in the direction of the arrows:

Figure 6 is a sectional view, partly in elevation, taken on the line 6—6 of Figure 3, and looking in the direction of the arrows; and

Figure 7 is a schematic wiring diagram showing the control circuits and mechanism by means of which the pumping mechanism of Figures 1 to 4 is controlled during its operation.

Referring particularly to Figures 1 to 6, the pumping mechanism will be seen as comprising a housing 10 formed in such fashion as to provide adjacent pump chambers 11 and 12. It will be observed that the bottoms 13 and 14 of these respective chambers slope downwardly and away from the common central portion 15 thereof. In this fashion fluid may be drained effectively from the chambers when the end plates (presently to be described) are removed therefrom. Reinforcing bands 16 and 17, respectively, extend about the chambers 11 and 12 and, at their lower portions, carry supporting feet 18 and 19, respectively.

End plates 20 and 21 serve to close the respective chambers 11 and 12, being secured in position by means of the two series of clamps 22 and 23, respectively. Fluid to be pumped is supplied to an inlet manifold 24 (see particularly Figure 4), the manifold being closed at one end by a plug or cap 25 and being provided with connections 26 and 27 that connect with inlet valves 28 and 29, respectively, these valves being provided with extensions 30 and 31 into the respective chambers 11 and 12, thus insuring that the fluid introduced into the pumping chambers is flowed easily therethrough at the bottom portions thereof. The valves 28 and 29 receive ball members 32 and 33, respectively, these ball members being of such weight that they float in the fluid being pumped. In this fashion, the ball members are readily displaced by the force of the flowing fluid, as illustrated by the position of the ball 32 in Figure 4, but when the fluid is static, the ball members seat against the valve seat to close the valve, as illustrated by the position of the ball member 33 in Figure 4. In order to avoid the possibility of fluid flow causing the valves to seat in the wrong direction, mechanical stops 34 are provided to limit the travel of the balls away from their seats.

Fluid is discharged from the chambers through an outlet pipe 34 that communicates with a discharge manifold 35 having connections 36 and 37 that communicate with valves 38 and 39, respectively.

2

tively (see Figure 5), these valves being formed with extensions 40 and 41, respectively, which extend downwardly adjacent the bottoms of the respective chambers 11 and 12. Ball members 42 and 43 are received in the respective valve chambers 38 and 39 and are of such weight that they sink in the static body of fluid that is to be pumped. Their mass is such, however, that they may be displaced upwardly to open the valves by the force of the fluid flowing upwardly as it is pumped out of the pumping chambers.

In order that a suitable pumping fluid under pressure may be supplied to the pumping chambers, fluid pressure connections 44 and 45 are provided with the respective chambers 11 and 12. These connections are formed with fittings 46 and 47, respectively, each of which in turn is connected respectively to vent valves 48 and 49 operated by the respective solenoids 50 and 51. The vent valves thus enable the chambers to be vented to the atmosphere.

The fittings 46 and 47 are also connected by means of connections 52 and 53 to air valves 54 and 55, respectively, these valves being controlled by the respective solenoids 56 and 57. The valves 54 and 55 thus serve as a means of supplying a pumping fluid under pressure to the respective pumping chambers 11 and 12.

In order that the pumping operation may be controlled effectively, the chambers 11 and 12 are provided with fittings 58 and 59, respectively, fitting 58 carrying a low level probe 60 and a high level probe or electrode 61, while fitting 59 carries high and low level probes or electrodes 62 and 63 (inasmuch as this mechanism is directly behind the corresponding elements in Figure 3, it is not shown other than to refer to it diagrammatically in Figure 7).

Referring to Figure 7, there is illustrated diagrammatically the electrical mechanism and circuits by means of which the pumping mechanism hereinabove described is operated in order to cause fluid to be pumped to accomplish the objects hereinabove mentioned as sought to be attained by the present invention. A suitable source of electricity is derived from an external circuit 64 and transmitted to supply wires 65 and 66. These supply wires furnish power to the primary windings of transformers 67 and 68, one secondary winding 69 of which is connected through electrical circuits 70 to the heater elements of the respective vacuum tubes 71 and 72. The vacuum tubes 71 and 72 operate, or cause the operation of, a plurality of relays R₁, R₂, R₃, R₄, R₅, and R₆.

Inasmuch as the circuit of each of the vacuum tubes 71 and 72 is identical, the description of the parts of one circuit will be made with simultaneous reference to the counterparts in the other circuit. To this end, circuits 73 and 74 connect the primaries of the respective transformers 67 and 68 to the supply wires 65 and 66, thus energizing the transformers and supply heater current for the heater elements of the vacuum tubes 71 and 72 and also current in the other secondary windings of these transformers for purposes presently to be described. Connecting wires 75 and 76 also connect the respective solenoids 50, 56, and 51, 57, to the supply wire 65. The operating coils of the relays R₃, R₅, and R₄, R₁ are energized, respectively, by the vacuum tubes 71 and 72. Current for this purpose is supplied from the plates of these respective tubes through the respective circuits 77 and 78 and wires 79 and 80. The return of the circuit is completed

through the wires 81 and 82, respectively, and wires 83 and 84 which are connected to one of the secondary windings of the respective transformers 67 and 68. These windings are grounded at 85 and 86 as are the cathodes 81 and 83 of the respective vacuum tubes 71 and 72.

The screen grids of the vacuum tubes 71 and 72 are connected to the wires 77 and 78 by the respective wires 89 and 90. The control grids of these vacuum tubes are connected through wires 91 and 92 to the respective high level probes or electrodes 61 and 63. These grids are also connected to the other end of the secondaries of the transformers 67 and 68 by means of wires 93 and 94.

The low level probes 60 and 62 are connected to normally open contacts 95 and 96 of the respective relays R₆ and R₁ by means of wires 97 and 98. These contacts also are connected to the respective wires 91 and 92 by means of wires 99 and 100.

The vent valve solenoids 50 and 51 are connected to the normally closed contacts 101, 102, by means of the respective wires 103, 104, these 25 normally closed contacts also being connected to the supply wire 66 by means of the respective wires 105 and 106.

The air solenoid valves 56 and 57 are connected to the normally open contacts 107 and 108 of the respective relays R₂ and R₃ by means of wires 109 and 110, these contacts also being connected by the respective wires 111 and 112 to the respective wires 113 and 114 which are connected to the normally closed contacts 115 and 116, respectively, of relays R₄ and R₅; to the normally open contacts 117 and 118 of the respective relays R₆ and R₁; and to the normally open contacts 119 and 120 of the respective relays R₅ and R₂.

40 The operating coils of the respective relays R₅ and R₂ are connected to the wire 65 by wires 69' and through the wires 121 and 122, respectively, with the respective open contacts 119 and 120 by means of the wires 123 and 124, respectively, and with the closed contacts 115, 116 through the respective wires 125 and 126. The closed contacts 115 and 116 of the respective relays R₄ and R₃ and the open contacts 119 and 120 of the respective relays R₅ and R₂ are connected together by means of respective wires 127 and 128, these wires also being connected to the respective wires 113 and 114 previously referred to.

To facilitate the manual operation of the pumping mechanism in order to empty and drain the system, manually operated switches 129 and 130, both of which are grounded, are connected to the respective wires 91 and 92.

Referring to the elements of Figure 6, it is to be observed that the vent valves and air valves 60 controlled by the solenoids 50, 51 and 56, 57 are open when the solenoids are energized. Moreover, the operation of the system causes the vent valves to be normally open. This results in a condition in which the chambers will immediately be filled with the fluid that is being pumped as soon as they are emptied.

It will further be observed that the relays R₄ and R₃ will be energized when the respective vacuum tubes 72 and 71 are energized, that is, when the respective tanks to which those vacuum tubes pertain are pumping. For example, when chamber 11 is pumping (exhausting itself), the vacuum tube 71 and relay R₃ are energized. Contrarywise, when chamber 12 is pumping, the 75 vacuum tube 72 and the relay R₄ are energized.

5

Therefore, under these circumstances, the normally closed contacts 116 and 115, respectively, are open during the times that the respective chambers 11 and 12 are pumping.

The vacuum tubes 71 and 72 are passing current when the respective electrodes 61 and 63 are grounded by the fluid in the respective chambers 11 and 12, and also when electrodes 60 and 62 are grounded by said fluid, providing contacts 95 and 96 are closed. In other words, when chamber 11 is filled and the electrode 61 grounded, the vacuum tube 71 passes current and causes the air valve 56 to admit air into the chamber 11 to force the fluid in such chamber out through the discharge port when relay R₅ is also energized.

The relays R₄, R₃, R₂, and R₅ control the air solenoids so that only one cylinder is pumping at a time. In other words, when one chamber is being emptied, the air solenoids prevent the other chamber from being emptied simultaneously.

The normally open contacts 117 and 118 of the respective relays R₄ and R₁ are closed when the respective vacuum tubes 71 and 72 are passing current. Under this condition, these contacts supply current to the respective relays R₅ and R₂ (provided the contacts of the respective relays R₄ and R₃ are closed). Actuation of the relays R₅ and R₂ closes the contacts 107 and 108, respectively, to energize the respective air valves 56 and 57 to cause, respectively, a pumping operation to take place in the respective chambers 11 and 12.

The secondaries of the transformers 67 and 68 provide a negative bias through current limiting resistors 93' and 94' on the control grids of the vacuum tubes 71 and 72, and under normal conditions these tubes will not be conducting. Inasmuch as the plate output of these tubes is connected to the relays R₁, R₄, R₃, and R₆, these relays will normally be de-energized. Under such condition, the normally closed contacts 101 and 102 of the relays R₆ and R₁ will energize the vent valves 50 and 51, respectively, allowing the chambers to fill with liquid.

If it be assumed that chamber 11 fills to the level of the electrode 61, the control grid of the tube 71 will be grounded and its negative bias removed so that the tube 71 will conduct. As a result, the relays R₅ and R₃ will be energized, and current will flow through the normally open contacts of the relay R₆ and through the normally closed contact of relay R₄. This results in energizing relay R₅ which closes contact 107, thus energizing the air solenoid 56, admitting compressed air into the chamber 11, and forcing its fluid through the outlet 34. Current will also flow through the coil of the relay R₅ closing the normally open contacts 107 and 119. The normally open contact 95 of relay R₆ will also close, grounding the control grid of the tube 71 through the electrode 60 which is immersed in liquid.

While chamber 11 is emptying, chamber 12 will be filling, and the electrode 63 will be grounded when the chamber 12 is filled. Grounding of the electrode 63 will remove the negative bias from the control grid of the vacuum tube 72 and cause it to pass current and energize relays R₄ and R₁. This will de-energize the vent valve solenoid 51 (causing the vent valve to close and air binding the chamber 12). The air valve 57 of chamber 12 will not open because the voltage applied across the normally open contact of relay R₁ will be unable to reach the air solenoid 75

6

because of the open contact 116 of the relay R₃. It will be recalled that this contact was opened when chamber 11 began to empty.

As a result of this tie-in or interlock, it is impossible for both tanks to empty simultaneously. As a result, the action of the two sets of the solenoid valves is synchronized. It will be observed that the opening of the contact 115 under these circumstances does not de-energize the air solenoid 56 because the contact 119 of the relay R₅ is connected in parallel with the contact of the relay R₄ and, being closed at this time, serves to hold the relay R₅ energized.

Turning back to the chamber 11, it will be seen that when the liquid level drops below the electrode 60, the grid of the vacuum tube 71 will again be biased negatively, cutting off the operation of this tube and de-energizing the relays R₃ and R₆. This will result in opening the normally open contacts of these relays, thus closing the air valve, deenergizing the relay R₅ and closing the normally closed contact 101 of the relay R₆. This energizes the vent valve solenoid 50 and allows the chamber 11 to refill. Re-contact of the liquid with the electrode 60 will not ground the grid of vacuum tube 71, because contact 95 of the relay R₆ is now open. As soon as the relay R₃ is de-energized, its contact 116 is allowed to close. Closing of the contact 116 of relay R₃ energizes the relay R₂, opening the air valve 57 so that chamber 12 begins to pump. If chamber 12 should empty before chamber 11 has been filled, the electrode 62 will break contact with the liquid in chamber 12 and remove the ground from the grid of the tube 72 and cut off the actuation of the tube. This will de-energize relays R₁ and R₄ and energize the vent valve 51 and allow the chamber to begin filling. However, compressed air will not be applied to chamber 11 until it is filled sufficiently to allow the level to reach the electrode 61. At this point, chamber 11 will begin to empty at once, since the contact of relay R₄ will be closed, allowing voltage to be applied to air solenoid 56.

It will be seen that the circuits hereinabove described provide complete and effective synchronization of the rise and fall of liquid in the two chambers, resulting in a reasonably smooth flow of liquid from the pumping unit.

In order that the rate of flow of fluid from the chambers may be controlled, an air pressure regulating mechanism 131 is provided in the compressed air line that furnishes operating fluid to the pumping mechanism. Such a mechanism will permit the rate of pumping to be varied in accordance with the available quantity of fluid to be pumped. At the end of an operation, the chambers may be emptied by closing the switches 129 and 130, thus forcing fluid from both of the chambers.

While the invention has been described with specific reference to the accompanying drawings, it is not to be limited save as defined in the appended claims.

We claim:

1. Fluid pumping mechanism, comprising two pump chambers, a first supply pipe communicating with the chambers for supplying a fluid to be pumped, a second supply pipe communicating with the chambers for supplying a pumping fluid thereto, a discharge pipe communicating with the chambers for discharging pumped fluid, first check valves in the connections of the first supply pipe with the respective chambers, second check valves in the connections of the discharge pipes

to the respective chambers, vent means for each of the chambers, first valves to control the respective vent means, second valves to control the second supply pipe to the respective chambers, high liquid level actuated means and low liquid level actuated means in each of the chambers, means actuated by said respective high level means to close said respective first valves, means actuated by said respective low level means to open said respective first valves and close said respective second valves, and means actuated by said respective high level means and the low level means in the other chamber for opening said respective second valves.

2. Fluid pumping mechanism, comprising two pump chambers, a first supply pipe communicating with the chambers for supplying a fluid to be pumped, a second supply pipe communicating with the chambers for supplying a pumping fluid thereto, a discharge pipe communicating with the chambers for discharging pumped fluid, first check valves in the connections of the first supply pipe with the respective chambers, second check valves in the connections of the discharge pipes to the respective chambers, vent means for each of the chambers, first valves to control the respective vent means, second valves to control the second supply pipe to the chambers, high liquid level actuated electrode and low liquid level actuated electrode in each of the chambers, an electronic amplifier associated with each of the chambers, a first set of relay contacts actuated by each of said amplifiers in response to the respective high liquid level actuated electrode for closing said respective first valves for opening said respective second valves to furnish pumping fluid to the respective chamber and for rendering the respective low liquid level actuated electrode effective, and a second set of relay contacts actuated by each of said amplifiers to render ineffective the opening of the second valve associated with the other chamber.

3. Fluid pumping mechanism, comprising two pump chambers, a first supply pipe communicating with the chambers for supplying a fluid to be pumped, a second supply pipe communicating with the chambers for supplying a pumping fluid thereto, a discharge pipe communicating with the chambers for discharging pumped fluid, first check valves in the connections of the first supply pipe with the chambers, second check valves in the connections of the discharge pipes to the chambers, means to open the second supply pipe to furnish pumping fluid to the chambers when the chambers are filled with fluid to be pumped, vacuum tubes associated with the chambers, circuits to energize the tubes, a first set of relay contacts actuated by each of the tubes controlling the valves for admitting pumping fluid and the vent valves of the respective chambers, a second set of relay contacts actuated by each of the tubes for preventing another of the tubes from causing its respective chamber to pump, and a third set of relay contacts for each of the tubes having circuits to maintain such last mentioned relay contacts in actuated condition and to complete the actuating circuit of the valves for admitting pumping fluid into the chambers.

4. Fluid pumping mechanism, comprising first and second pump chambers; first and second inlet check valves through which fluid to be pumped may be supplied to said first and second chambers, respectively; first and second outlet check valves through which the pumped fluid

may be discharged from said first and second chambers, respectively; first and second vent valves for venting to the atmosphere said first and second chambers, respectively; first and second supply valves for supplying a pumping fluid to said first and second chambers, respectively; first and second high liquid level actuated means in said first and second chambers, respectively; first and second low liquid level actuated means in said first and second chambers, respectively; means responsive to said first and second high liquid level actuated means for closing said first and second vent valves, respectively; means responsive to said first and second low liquid level actuated means for opening said first and second vent valves, respectively, and for closing said first and second supply valves, respectively; and means responsive to both a respective high liquid level actuated means and an opposite low liquid level actuated means for opening said first and second supply valves, respectively.

5. Fluid pumping mechanism, comprising first and second pump chambers; first and second inlet check valves through which fluid to be pumped may be supplied to said first and second chambers, respectively; first and second outlet check valves through which the pumped fluid may be discharged from said first and second chambers, respectively; first and second vent valves for venting to the atmosphere said first and second chambers, respectively; first and second supply valves for supplying a pumping fluid to said first and second chambers, respectively; first and second high liquid level actuated electrodes in said first and second chambers, respectively; first and second low liquid level actuated electrodes in said first and second chambers, respectively; first and second amplifiers associated with said first and second chambers, respectively; first and second sets of relay contacts actuated by said respective first and second amplifiers in response to said respective high liquid level actuated electrodes for closing said respective first and second vent valves, for opening said respective first and second supply valves, and for rendering said respective low liquid level actuated electrodes effective; and third and fourth sets of relay contacts actuated by said first and second amplifiers for rendering ineffective the opening of second and first supply valves, respectively, whereby only one chamber can be pumped at a time.

6. A mechanism according to claim 5 wherein the amplifiers are electron tubes having control grids and include means for normally biasing the control grid of each tube negatively to prevent the respective tubes from conducting and means for grounding the negative bias through the respective high liquid level actuated electrodes when the respective chambers are full to permit the respective tubes to conduct and thereby actuate the relay contacts.

RALPH HORTON.
